UNITED STATES PATENT OFFICE.

MIDDLETON H. ROBERTS, OF ROLFE, IOWA.

EXPLOSIVE-ENGINE.

SPECIFICATION forming part of Letters Patent No. 743,332, dated November 3, 1903.

Application filed August 17, 1901. Serial No. 72,378. (No model.)

To all whom it may concern:

Be it known that I, MIDDLETON H. ROBERTS, residing at Rolfe, in the county of Pocahontas and State of Iowa, have invented a new and Improved Explosive-Engine, of which the following is a specification.

My invention seeks to provide a new and improved engine adapted to operate under an explosive force of working agent of mixed air and gas or gasolene; and it primarily seeks to provide an engine of this character of a simple and compact construction capable of being operated under an economical use of the working agent and having its several parts co-operatively arranged to provide for a uniform and effective action.

In its generic nature my invention comprehends a working cylinder, an explosion-chamber communicating with one end thereof, and a supplemental chamber held in communication with both ends of the working cylinder and adapted to receive the exploded mixture under pressure and at predetermined times feed the mixture against the front or inner end of the working piston to assist in propelling it toward the explosion end. Suitably and automatically arranged valve devices for regulating the inflow of the working agent and the flow of the exploded mixture to the supplementary chamber and the cylinder and to the exhaust are provided and adapted to co-operate with cam or tripping mechanism controlled by the drive-shaft for setting and operating the several valves at predetermined times.

My invention in its more subordinate features consists in certain details of constructions, peculiar and novel arrangements of parts, including specific constructions of cam and valve shifting devices for effecting a proper flow of the working agent first into the cylinder as the piston recedes from the fire or exploding end and simultaneously exhausting the exploded mixture at the rear of the piston, then cutting off the working-agent supply and opening up an escape to the exploded mixture of the supplementary chamber during the forward thrust of the piston, then drawing in a new charge, and then opening up prior exploded charge to the rear of the piston as the new charge of the working agent is being compressed, all of the said parts

being substantially arranged as hereinafter described in detail, illustrated in the drawings, and specifically pointed out in the appended claims.

Referring now to the accompanying drawings, in which like numerals, letters, and characters indicate like parts in all the figures, Figure 1 is a horizontal section of my improved engine, taken practically on the line 1 1 of Fig. 2. Fig. 2 is a side elevation of the same looking in the direction of the arrow in Fig. 1, a part of the valve-casing being shown in section on the line 2 2 of Fig. 1. Fig. 3 is a transverse section on the line 3 3 of Fig. 1. Fig. 4 is a similar view on the line 4 4 of Fig. 1. Fig. 5 is a horizontal section of the slide-valve for controlling the compressed mixture to the piston-cylinder, said valve being shown set to the position for exhausting said mixture from the cylinder. Fig. 6 is a side view, and Fig. 6^a is an end view, of the cam mechanism for tripping the valves *c* and *d*, hereinafter fully explained. Fig. 7 is a side elevation of the machine looking in the direction of the arrow *b*, parts being in section on the line 7 7 of Fig. 1.

In the practical construction of my invention the same embodies a suitable foundation or base 10, upon one end of which, on vertical members 10^a and in suitable bearings thereon, is mounted the drive-shaft *G*, formed with a single crank *g* and carrying at one end a fly-wheel *g'*, and at the other end it has a cog-wheel *g''*, the purpose of which will be presently explained.

A chamber *X* is located under the cylinder 20, and said chamber is formed by the side walls 10^a 10^b, the head or end wall 10^x, (see dotted lines, Fig. 2,) the cross-wall 10^c, and the crown or top 10, and the base 10^y. The cylinder 20 at its front end has an explosion-compartment 20^a, and the said explosion-compartment 20^a at one side communicates with pockets 21 22, the upper one of which has an exhaust-pipe *y*, which joins with the main exhaust-pipe *V*, (presently again referred to,) and the pocket 21 has an offtake *e*, that empties into the chamber *X* and has a check-valve *E*, as shown. The pockets 21 22 are normally closed to the explosion end of the cylinder 20 by the valves *C* and *D*, as shown in Fig. 1, by reference to which it will be no-

ticed these valves open outward and are held closed by the spiral springs R R, mounted on valve-stems r r.

Z' Z² designate plunger-rods held to slide 5 in suitable bearings in the engine-framing, the outer ends of said rods Z' Z² being pivotally supported on the swinging arms 3^a, the free ends of which have roller-bearings 3^b, held to engage with cam-disks 1 and 2, mounted 10 on the stub-spindle 15, made fast to or formed integrally upon the gear-wheel G^x, held to mesh with the gear-wheel g² on the drive-shaft G, said wheel G^x being twice the diameter of the wheel g², so as to provide for 15 making one revolution of the gear G^x as the gear g² makes two revolutions, whereby to operate the valves C and D at every alternate thrust of the piston.

I designates an eccentric on the crank-shaft G, which has a pitman I' connected thereto and which joins by the adjustable clip member i with the slide-valve A', slidably mounted in the valve-casing a on the rear end of the working cylinder and at that 25 side diametrically opposite the valve-pockets containing the valves C and D. The valve A' is double-acting, is of the D type, its groove or channel d being adapted to alternately cut off the exhaust-port v, that leads 30 to the main exhaust V, or bring said port v into communication with the outlet M at the inner or front end of the working cylinder, the said parts, valve A', its shifting devices, and the ports M and v, being relatively so arranged 35 that when the valve A' covers both ports M and v the exhaust passes from the working cylinder to the offtake-pipe V, and when the valve is pushed to the position shown in Fig. 1 the mixture in chamber X is permitted 40 to pass through the pipe U that joins the chamber X and valve-chamber a for forcing the piston S to the outer or rear end of the cylinder.

At the rear end of cylinder and opposite 45 the valves C and D is a laterally-extending pocket or space b', that forms a part of the explosion end of the cylinder and which communicates through the valved inlet b² with working-agent feed-space b³, into which the 50 mixed air and gas conveyer pipe b⁴ discharges. The inlet b² is normally held closed by a valve B, of the upwardly-acting kind, normally held to its closed position by the retractile spring devices and adapted to open by the suction 55 action above it, as will presently more fully appear.

The chamber X is also provided with an automatic air-feed controlled by a check-valve F, which, as also the check-valve E before referred to, is the common form of check-valve, and the valve E is utilized to prevent pressure in the chamber X flowing back to the explosion-chamber, and valve F is utilized to admit air to the chamber when there 65 is no explosion in the cylinder on account of too high speed.

Assuming the parts to be in the position

shown in Fig. 1, the piston being at the limit of its inward stroke and a working mixture present in the extension-chamber 20^a, now 70 assume the mixture exploded and the piston starting on its outstroke. As the piston is propelled forward by the exploded mixture the valve A' is open to exhaust, while the valves C and D are closed, as is also the check-valve E, it being also understood that the initial pressure in the chamber X is atmospheric pressure only. Just before the piston completes its first outstroke the valve D is opened by means of the cam 2, which co-operates with the swinging member 3, attached to the rod Z², that acts on the rod r of the valve D, it being understood that the movement of said cam 2 is so timed as to cause the valve D to open just before the piston 85 reaches the front end or limit of its first forward stroke. This completes the first part of the cycle of operations. As the piston makes its first return stroke the burned or spent mixture is expelled from the chamber 90 20^a through the valves D and E into the chamber X. The valve A' during this stroke is open to bring the chamber 20 in connection with the chamber X to obtain an equal pressure on each side of the piston during this 95 the first return stroke. During this entire stroke the valve C remains closed. As the piston reaches the limit of its first return stroke the valve C by means of its gearing with cams H and rods Z' is opened for an instant to allow the residue burned mixture to exhaust from chamber 20^a, it being understood that since the valve E is a one-way check-valve opening only toward the chamber X none of the mixture therein can escape to 100 atmosphere through said valve C and its exhaust-pipe. This completes the second part of the cycle of operations. As the piston starts on its second forward stroke the valve A' is shifted to exhaust the mixture in front 105 of the piston, while a new charge is drawn into the chamber 20^a through the valve B, which is now open, the valves C, D, and E being closed. This completes the third portion 110 of the cycle of operations. As the piston returns on its second return stroke the valves B, C, D, and E remain closed to allow the unexploded mixture in chamber 20^a to be compressed. The valve A', however, is shifted to open communication with chamber 115 X to allow the mixture therein to come in behind the piston, and since in practice it is found that this mixture is at a pressure greater than atmosphere (from twenty-five to thirty pounds) this pressure will assist in forcing 120 the piston back, and thereby help to compress the unexploded mixture in chamber 20^a. This completes the full cycle of operations. Upon the explosion of the mixture in the chamber 20^a the cycle of operations above described is again repeated. Should the engine 125 run up to an excess speed and the igniting mechanism fail to explode the mixture in the chamber 20^a and the mixture in chamber X

reduce to a pressure less than that of atmosphere, the valve F will open and allow air to enter the chamber X to restore the balance of pressure.

- 5 From the foregoing, taken in connection with the accompanying drawings, it is thought the complete operation and the advantages of my improved explosive-engine will be readily explained.
- 10 While I prefer to combine and arrange the several parts as shown and described, the same may be modified and the details of construction varied without departing from the scope of the appended claims.
- 15 W designates the usual water chamber or jacket for cooling the cylinder.
- Having thus described my invention, what I claim, and desire to secure by Letters Patent, is—
- 20 1. In an explosive-engine of the character described, the combination with the working cylinder, the piston, the drive-shaft, and the working-agent feed-pipe having an automatically-controlled valve; of a pair of valve-chambers in communication with the explosion end of the cylinder, each having a valved outlet, one of said chambers discharging into an exhaust, a supplemental chamber X, communicating with the other valved chamber,
- 25 30 a valved chamber a communicating with the front end of the cylinder and with an exhaust, and with the chamber X, a D-valve slideable in said chamber, for alternately opening up communication between the cylinder and the chamber X, and said cylinder and the exhaust, and automatically - operated shifting devices, controlled by movement of the drive - shaft for operating the several

valves aforesaid, whereby the exploded mixture of one charge will be made to assist in 40 the compression of the nearest succeeding new charge, substantially as shown and for the purposes described.

2. In an explosive-engine of the character described, the combination with the drive-shaft, the cylinder, the piston, and the working-agent feed, said feed discharging into the rear end of the cylinder, and having a suction-operated valve; of the spaces 21 22 communicating with the explosion end of the cylinder, an upper and lower valve-chamber, coöperating with the spaces 21 21, respectively, the valves C and D, normally closing off the valve-chambers from said spaces, the upper chamber having an exhaust, the 55 lower an offtake e, having a check-valve E, the valves C and D being spring-held to their closed position, the pusher-rods Z' Z², cams 1 and 2, coöperating therewith and controlled by movement of the drive-shaft, the supplemental chamber X, into which offtake e discharges, said chamber X having an offtake U, the valve-chamber a, communicating with the front end of the cylinder, the exhaust V connected to said chamber a, the slide-valve 65 A, and means for operating said valve at predetermined intervals, whereby the exploded mixture of one charge will assist the piston in compressing the next succeeding new charge, all being arranged substantially as shown 70 and for the purposes described.
